US0D1021521S

(12) **United States Design Patent** (10) Patent No.: **US D1,021,521 S**
(45) Date of Patent: ** Apr. 9, 2024

(54) **BABY FOOD MAKER**

(71) Applicant: **MARVELOUS LINK CORP.**, San Leandro, CA (US)

(72) Inventor: **Yingjun Huang**, San Leandro, CA (US)

(73) Assignee: **MARVELOUS LINK CORP.**

(**) Term: **15 Years**

(21) Appl. No.: **29/897,005**

(22) Filed: **Jul. 11, 2023**

(51) LOC (14) Cl. 31-00

(52) U.S. Cl.

USPC **D7/384**; D7/368

(57) **CLAIM**

The ornamental design for a baby food maker, as shown and described.

DESCRIPTION

FIG. 1 is a top perspective view of a baby food maker, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the baby food maker, which form no part of the claimed design.

1 Claim, 8 Drawing Sheets
